CLAIM

The ornamental design for a baking tray as shown and described.

DESCRIPTION

FIG. 1 is a front, left and top perspective view of a baking tray, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2.

FIG. 11 is an enlarged view of detail 11 in FIG. 7; and,

FIG. 12 is an enlarged view of detail 12 in FIG. 8.

The dot-dash broken lines in FIGS. 1-2 and 7-12 depict the boundaries of the enlargements that form no part of the claimed design.

1 Claim, 12 Drawing Sheets
